(57) **CLAIM**

The ornamental design for a child seat, as shown and described.

DESCRIPTION

FIG. 1 is a perspective view of a child seat in a first “rear-facing” position with a support leg shown in an open position;

FIG. 2 is a right side elevational view of the child seat; FIG. 3 is a left side elevational view of the child seat; FIG. 4 is a front side elevational view of the child seat; FIG. 5 is a rear side elevational view of the child seat; FIG. 6 is a top plan view of the child seat;

FIG. 7 is a perspective view of the child seat in a second “forward-facing” position with the support leg in a closed position;

FIG. 8 is a right side elevational view of the child seat; FIG. 9 is a left side elevational view of the child seat; FIG. 10 is a front side elevational view of the child seat; FIG. 11 is a rear side elevational view of the child seat; and, FIG. 12 is a top plan view of the child seat.

The bottom of each car seat is not seen during use and therefore does not form a part of the claimed invention.
